UNITED STATES PATENT OFFICE.

OTAKAR VALASEK, OF CHICAGO, ILLINOIS, ASSIGNOR OF ONE-HALF TO PETER BERKEY,
OF CHICAGO, ILLINOIS.

FASTENING DEVICE FOR FOLDERS, ENVELOPS, &c.

1,181,269.

Specification of Letters Patent.

Patented May 2, 1916.

Application filed January 25, 1915. Serial No. 4,180.

To all whom it may concern:

Be it known that I, OTAKAR VALASEK, a citizen of the United States, residing at Chicago, county of Cook, State of Illinois, have invented a certain new and useful Improvement in Fastening Devices for Folders, Envelops, &c., and declare the following to be a full, clear, and exact description of the same, such as will enable others skilled in the art to which it pertains to make and use the same, reference being had to the accompanying drawings, which form a part of this specification.

My invention has for its object to provide advertising folders or circulars and envelops or containers made of comparatively strong stiff material with simple and effective fastening devices produced by simply cutting small peculiarly shaped slits 20 in the body thereof.

The various features of novelty whereby my invention is characterized will herein-after be pointed out with particularity in the claims; but, for a full understanding of 25 my invention and of its object and advantages, reference may be had to the following detailed description taken in connection with the accompanying drawings, wherein:

Figure 1 is an elevation of a folder arranged in accordance with the present invention, the folder being in an unfolded or flat condition; Fig. 2 is a perspective view, on an enlarged scale, of the device shown in Fig. 1, partly folded; Fig. 3 is an elevation 30 of the device shown in Figs. 1 and 2, folded and fastened; Fig. 4 is an end view, looking toward the left from the right hand end of Fig. 3, on an enlarged scale; Figs. 5, 6 and 7 are perspective views, on an enlarged 35 scale, of the portions of the folder in the vicinity of the fastening means, illustrating the effect of different kinds of stresses on the fastening device; Figs. 8, 9, 10, 11 and 40 12 are views corresponding, respectively, to Figs. 1, 2, 3, 4 and 7, illustrating my invention applied to a modified form of folder; Figs. 13, 14 and 15 are views corresponding 45 to Figs. 1, 4 and 7, illustrating the fastening device applied to a still different form of folder; Fig. 16 is an elevation of an envelop or container in a flat unfolded condition and embodying a fastening device arranged in accordance with the present invention; Fig. 17 is a view of the envelop of 50 Fig. 16 folded and fastened; Fig. 18 is a

perspective view of the folder or envelop in its fastened condition; and Figs. 19, 20 and 21 are views corresponding to Figs. 16, 17 and 18, respectively, illustrating a double fastening device as distinguished from the single fastening device shown in the other figures.

Generally speaking, my invention consists in cutting in the paper or other material of which the folder, envelop or container is made, a plurality of peculiarly shaped slits which will produce hooked tines adapted to be slipped past each other and interlock with the body portions of the folder, envelop or container and prevent accidental separation under the various conditions apt to be encountered.

Referring to Figs. 1 to 7 of the drawings, 1, 2, 3 and 4 represent four sections of a card or folder adapted to be folded into a packet comprising two inner sections, 1 and 4, and two outer sections, 2 and 3. In order to prevent the device from unfolding, it is customary to place a sticker or other fastening device over the two edges formed between the sections 1 and 2 and sections 3 and 4, respectively, when these edges lie side by side as they do in the folded packet. In accordance with my invention, I cut two slits, 5 and 6, in the body of the folder, the first being symmetrically disposed with respect to the dividing line between the sections 1 and 2 and the other being symmetrically disposed with respect to the dividing line between the sections 3 and 4, and the two together being symmetrically disposed with respect to some line extending longitudinally of the folder. Each of the slits is made in the form of a C having the free ends curled inwardly. When the device is folded, two oppositely facing tines, 7 and 8, are produced in the two free edges, these tines being so positioned that they may be slipped past each other and interlock the members of which they form part together.

The important feature of the present invention consists in the small inward curl formed in the slit at what is the base of the tine, this producing a small hook, 9, at the base of each of the tines; which hook drops down beside and overlaps the body portion of the section or group of sections with which the tine is interlocked and serving as the barb on a fish hook to prevent the withdrawal of the tine. Since each of the two

tines is provided with the small hook or barb, neither tine can be withdrawn accidentally after the fastening has been made.

In Fig. 5 the parts are illustrated in their normal interlocked conditions. If now the folder be distorted by forces acting in the direction of the arrows in Fig. 6, the barbs or hooks, 9, will travel to the positions indicated in Fig. 6 after which further relative movement of the members of the folder in the direction of the arrows will be impossible without destroying the folder.

In Figs. 8 to 11 I have illustrated a folder made of three sections only; there being a slit, 5, associated with the sections 1 and 2, just as in the other form, and a slit, 10, extending inwardly from the lower free edge of the section 3 and corresponding to one-half of the slit 6 in the first form. When this folder is folded there is a tine or tongue, 7, of double thickness and a tine or tongue, 11, of single thickness.

In the arrangement shown in Figs. 13 to 15 the folder is made of two sections, 12 and 13, and extending inwardly from the free edge of each of these two sections is a slit, 14, corresponding to the slit 10 in the form illustrated in Figs. 8 to 12. When this device is folded on itself there are two interlocking tines, 15, each of a single thickness of material and provided with a hook or barb 9.

In Figs. 16 to 18 I have illustrated my invention applied to an envelop in which there is a body section, 16, having end flaps, 17, and top and bottom flaps, 18 and 19. Extending inwardly into the flap 18 from the line, imaginary or otherwise, between the flap 18 and the body member 16 is a curved slit, 20, corresponding to the slits 10 and 14 previously described and having at its inner end the hook or curl, 21. Extending inwardly from the bottom edge of the flap 19 is a slit, 22, corresponding to the slit 20; the two slits being symmetrically disposed with respect to a longitudinal axis. When the envelop is folded, the slits 20 and 22 provide two hooked or barbed tines, 23, which interlock.

In Figs. 19 to 21 I have shown an envelop similar to that illustrated in Figs. 16

to 18 but provided with duplicate fastening devices; there being two slits, 24 and 25, corresponding to the slit 20 in Fig. 16 but disposed on opposite sides of the central longitudinal axis and preferably oppositely disposed; and there being also two other slits, 26 and 27, corresponding to the slit 22 in Fig. 16, so disposed as to coöperate with the tines formed by the slits 24 and 25 when the envelop is folded. Thus it will be seen from Figs. 20 and 21, the slits 24 and 25 produce the hooked or barbed tines, 28 and 29, which are oppositely disposed and thus secure the final closing flap, 30, of the envelop very firmly.

I claim:

1. A device made of sheet material having two engaging members, said members having opposed curved slits forming opposed overlapping barbed tines, the barb on each tine being on the under edge and adjacent to the base thereof.

2. A device made of sheet material having two engaging members, one of said members having a curved slit extending inwardly from the edge and having its inner end curled upon itself so as to produce a tine formed with a barb at the base, and the other of said members having therein a curved slit oppositely disposed to the aforesaid slit and forming a tine complementary to the aforesaid tine and adapted to overlap and interlock with the same.

3. A device made of sheet material having two engaging members the corresponding free edges of which lie side by side, each of said members having a curved slit extending inwardly from its aforesaid edge to form a tine, the inner end of each of said slits being curled so as to produce a barb at the base of the tine, said slits being oppositely disposed so as to bring the tines in opposed relation to each other and permit them to interlock with the barbs engaging with the body portion of said members.

In testimony whereof, I sign this specification in the presence of two witnesses.

OTAKAR VALASEK.
